UNITED STATES PATENT OFFICE.

JOHN PAXTON PETTY, OF READING, ENGLAND.

TEMPORARY BINDER OR LOOSE-SHEET HOLDER.

1,142,455.

Specification of Letters Patent. Patented June 8, 1915.

Application filed February 26, 1914. Serial No. 821,188.

To all whom it may concern:

Be it known that I, JOHN PAXTON PETTY, a subject of His Majesty the King of England, residing at Reading, Berkshire, England, have invented certain new and useful Improvements in Temporary Binders or Loose-Sheet Holders, of which the following is a specification.

This invention relates to temporary binders or loose sheet holders and is particularly directed to binders or holders of the kind in which a pair of sheet or the like clamping bars, associated with a pair of covers and a telescoping back strip are drawn together to clamp the sheets by means comprising a rotating element such as a rod or spindle located longitudinally of the clamping bar.

By and in accordance with the present invention a back or loose strip telescoping in chambered covers of the binder is fitted to the binder in such manner that it is positively adjusted simultaneously and in accordance with the adjustment of the clamping bars through the medium of the rotating element and an endless band operatively connected therewith and attached to the back strip so as to move the attached end of the back strip backward and forward according to the direction of rotation of the rotating element.

In order that the invention may be clearly understood and readily carried into effect reference may be had to the accompanying drawings which illustrate a convenient embodiment, on which drawings:

Figure 1 is a plan of the back cover with parts broken away to show the mechanism in the interior thereof. Fig. 2 is a transverse section, drawn to an enlarged scale, on line 2—2 of Fig. 1; but in this view the chain 15 is not illustrated so as to present a clear illustration of the endless band. Fig. 3 is a part sectional plan view of the front cover.

The covers or backs 1 and 2 comprise clamping bars 3 and 4 pivoted thereto, the lower clamping bar 4 having journaled therein a rod 5 rotatable for adjusting the clamping bars in relation to one another. A back or loose strip 6 is passed around the clamping bars and the ends of such strip pass into cavities or chambers in the covers 1 and 2. This strip is so connected to the rod 5 that when the latter is operated to adjust the clamping bars, such strip is correspondingly adjusted so as always to be a

good fit around the clamping bars. As illustrated one end of the strip 6 is connected to an endless band 7 operated from the spindle 5 to effect which operation the endless band 7 for the whole or for a portion of its length (preferably the latter) is comprised of a length of chain 8 which gears with a sprocket wheel 9 fixed to the spindle 5, the remaining portion in the case of a part chain band being formed of a strip of textile material which passes around a roller 10 secured in relation to the forward end of the cover. This roller 10 is resiliently mounted such as by the ends thereof being fitted within slots 12 of the mounting 13 and being connected to springs 14 tending to increase the distance between the roller 10 and spindle 5, whereby the endless band is always maintained in a taut condition. Thus when the cover of the illustrated binder is opened the band is still maintained in a taut condition as the roller is moved by the spring along the slots to counterbalance the reduction in distance between the roller 10 and spindle 5, which would normally be caused in virtue of the cover hinge plates 11 having pivotal connection to the clamping bars at a point which lies to one side of the axis of the spindle 5, as shown in Fig. 3.

The clamping bars are conveniently adjusted by chains 15 detachably secured to clamping bar 3 and engaging with sprocket wheels 16 secured to the spindle 5 which is journaled in the other clamping bar 4. Thus it will be seen that by rotating the spindle 5 in one direction the clamping bars will be drawn together by the engagement of the sprocket wheels 16 and chains 15, while by the engagement of the chain 7 and sprocket wheel 9 the end 6^a of the loose or back strip 6 will be drawn into the cover a corresponding extent thus keeping the back strip a good fit around the clamping bars. Upon rotating the spindle 5 in the reverse direction the length of back strip passing out from the covers is increased to the same amount as the increase of the length of chain between the clamping bars. It will be seen that the use of the back strip 6 does not preclude the clamping bars being moved a sufficient distance apart to permit the loose-ended sheet-registering leather thongs 23 being disengaged from the cover 1 for the removal of sheets therefrom or replacement thereon.

To lock the spindle 5 against rotation any

- appropriate means may be employed, and conveniently a multiple disk friction clutch such as set forth in English Patent No. 2971 of 1912 may be employed.
- 5 In order that the chains 15 may be prevented from sagging the ends passing into the cover 2 are secured to the end 6^a of the strip 6, and as they are thus secured in relation to the endless band 7 such ends are 10 given a movement equal to that imparted to the chains by the sprocket wheels 16, thus preventing the links jamming between the clamping bar 4, and cover 2. The end 6^a of the strip has secured thereto a metal plate 6^c 15 which provides a convenient means of securing the chains 15 and endless band 7 to the strip 6, and also for maintaining the edge 6^a thereof parallel to the edge of the cover 2.
- The end 6^b of the back strip 6 is preferably resiliently secured in the cavity of the cover 1 such as by means of the spring 19 located around the rod 20, and between the head 21 thereof and the guide 22 fixed to the cover, said rod 20 being secured to the 25 cover. This spring 19 thus always draws the end 6^b of the strip into the cover to thereby maintain a tight fit of the strip around the clamping bars, and serves to take up slackness when the binder is opened.
- 30 Registration of the sheets is conveniently effected by loose ended longitudinally flexible and transversely relatively rigid members 23, arranged through the clamping bars and terminating without fastening in one or 35 both of the covers.
- I claim:
1. The combination of clamping bars, chambered covers, a back strip telescoping in the chambers of the covers, clamping bar 40 actuating mechanism comprising a revolving rod running parallel with the clamping bars, and an endless band attached to the back strip and having operative connection with said revolving rod whereby the back strip is adjusted simultaneously and in accordance with the adjustment of the clamping bars.
  2. The combination of clamping bars, chambered covers, a back strip telescoping 50 in the chambers of the covers, clamping bar actuating mechanism comprising a revolving rod running parallel with the clamping bars, a sprocket wheel on said revolving rod, a binding chain coöperating with said sprocket wheel arranged through said clamping bars and connected at one end to said back strip, and an endless band attached to the back strip and having operative connection with said revolving rod whereby the back strip is adjusted simultaneously and in accordance with the adjustment of the clamping bars, and the binding chain is prevented from jamming or fouling the clamping bar actuating mechanism, and a resiliently mounted guide for said band.
  3. The combination of clamping bars, 60 chambered covers, a back strip telescoping in the chambers of the covers, and telescoping back strip actuating mechanism comprising an endless band and a revolving ele-

70 chambered covers, a back strip telescoping in the chambers of the covers, clamping bar actuating mechanism comprising a revolving rod running parallel with the clamping bars, a sprocket wheel on said revolving rod, an endless band attached to the back strip and arranged to co-act with said sprocket wheel to be operated thereby, and a resiliently mounted guide for said band, whereby the back strip is adjusted simultaneously and in accordance with the adjustment of the clamping bars and the endless band is maintained at all times in a taut state.

4. The combination of clamping bars, 80 chambered covers, a back strip telescoping in the chambers of the covers, clamping bar actuating mechanism comprising a revolving rod running parallel with the clamping bars, an endless band attached to the back strip and having operative connection with said revolving rod whereby the back strip is adjusted simultaneously and in accordance with the adjustment of the clamping bars, and yielding means acting on said endless band to maintain the back strip 85 wrapped closely around the clamping bars.

5. The combination of clamping bars, chambered covers pivoted thereto, a back strip telescoping in the chambers of the covers, clamping bar actuating mechanism comprising a revolving rod running parallel with the clamping bars, a sprocket wheel on said revolving rod, a binding chain coöperating with said sprocket wheel arranged through said clamping bars and connected 90 at one end to said back strip, and an endless band attached to the back strip and having operative connection with said revolving rod whereby the back strip is adjusted simultaneously and in accordance with the adjustment of the clamping bars, and the binding chain is prevented from jamming or fouling the clamping bar actuating mechanism, and a resiliently mounted guide for 95 said band.

6. The combination of clamping bars, chambered covers pivoted thereto, a back strip telescoping in the chambers of the covers, clamping bar actuating mechanism comprising a revolving rod running parallel with the clamping bars, a sprocket wheel on said revolving rod, a binding chain coöperating with said sprocket wheel arranged through said clamping bars and connected 100 at one end to said back strip, a second sprocket wheel on said revolving rod, an endless band attached to the back strip and arranged to co-act with said second sprocket wheel to be operated thereby and a resiliently mounted guide for said band.

7. The combination of clamping bars, chambered covers, a back strip telescoping in the chambers of the covers, and telescoping back strip actuating mechanism comprising an endless band and a revolving ele- 105 110 115 120 125 120 125

ment arranged to co-act with said band to draw the telescoping back strip inward or outward of the cover according to the direction of rotation of the revolving element 5 substantially as described.

8. The combination of clamping bars, chambered covers, a back strip telescoping in the chambers of the covers, telescoping back strip actuating mechanism comprising 10 a sprocket wheel, an endless band arranged to co-act with said sprocket wheel to be operated thereby to draw the telescoping back strip inward or outward of the cover according to the direction of rotation of the 15 revolving element, and a resiliently mounted member for said band, whereby the back strip is adjusted simultaneously and in accordance with the adjustment of the clamping bars and the endless band is maintained 20 at all times in a taut state.

9. The combination of clamping bars, chambered covers, a back strip telescoping in the chambers of the covers, and having a transversely rigid edge, clamping bar actuating mechanism comprising a revolving rod running parallel with the clamping 25 bars, sprocket wheels on said revolving rod, binding chains coöperating with said sprocket wheels arranged through said 30 clamping bars and connected at one end to said rigid edge of said back strip, and an endless band attached to said rigid edge of said back strip and having operative connection with said revolving rod whereby the 35 back strip is adjusted simultaneously and in accordance with the adjustment of the clamping bars, and the binding chain is prevented from jamming or fouling the clamping bar actuating mechanism.

40 10. The combination of clamping bars, chambered covers pivoted thereto, a back strip telescoping in the chambers of the covers and having a transversely rigid edge, clamping bar actuating mechanism comprising 45 a revolving rod running parallel with the clamping bars, sprocket wheels on said revolving rod, binding chains coöperating with said sprocket wheels arranged through said clamping bars and connected at one end 50 to said rigid edge of said back strip, and an endless band attached to said rigid edge of said back strip and having operative connection with said revolving rod whereby the back strip is adjusted simultaneously and in 55 accordance with the adjustment of the clamping bars, and the binding chain is prevented from jamming or fouling the clamping bar actuating mechanism, and a resiliently mounted guide for said band.

60 11. The combination of clamping bars, chambered covers associated therewith to have pivotal movement in relation thereto,

binding means arranged through said clamping bars, means carried by one of said clamping bars coöperating with said binding means for fastening or releasing the clamping bars, a back strip adapted to telescope into the chambers of said covers, and connections between said back strip and said means coöperating with the binding means 65 to adjust the back strip simultaneously and in accordance with the adjustment of the clamping bars.

12. The combination of clamping bars, chambered covers associated therewith to 70 have pivotal movement in relation thereto, binding means arranged through said clamping bars, means carried by one of said clamping bars coöperating with said binding means intermediate of the ends thereof 75 for fastening or releasing the clamping bars, a back strip adapted to telescope into the chambers of said covers, and connections between said back strip and said means coöperating with the binding means to adjust 80 the back strip simultaneously and in accordance with the adjustment of the clamping bars.

13. The combination of clamping bars, chambered covers associated therewith to 90 have pivotal movement in relation thereto, binding means arranged through said clamping bars, means carried by one of said clamping bars coöperating with said binding means for fastening or releasing the 95 clamping bars, a back strip adapted to telescope into the chambers of said covers, and an endless band connection between said back strip and said means coöperating with the binding means to adjust the back strip simultaneously and in accordance with the 100 adjustment of the clamping bars.

14. The combination of clamping bars, chambered covers associated therewith to have pivotal movement in relation thereto, 105 binding means arranged through said clamping bars, means carried by one of said clamping bars coöperating with said binding means for fastening or releasing the clamping bars, a back strip adapted to telescope into the chambers of said covers, an 110 endless band connection between said back strip and said means coöperating with the binding means to adjust the back strip simultaneously and in accordance with the adjustment of the clamping bars and a resiliently mounted guide for said endless band.

In testimony whereof I affix my signature in presence of two witnesses.

JOHN PAXTON PETTY.
